UNITED STATES PATENT OFFICE.

EDWARD WHITE, OF HAWTHORNE, NEW JERSEY.

BLANKET WASHING AND DRYING MACHINE.

1,270,351.

Specification of Letters Patent. Patented June 25, 1918.

Application filed April 25, 1916. Serial No. 93,558.

To all whom it may concern:

Be it known that I, EDWARD WHITE, a citizen of the United States, residing at Hawthorne, in the county of Passaic and State of New Jersey, have invented certain new and useful Improvements in Blanket Washing and Drying Machines; and I do hereby declare the following to be a full, clear, and exact description of the invention, such as will enable others skilled in the art to which it appertains to make and use the same.

This invention relates to improvements in textile printing machines, and has for its object to provide means for washing and cleansing the endless web or blanket, as it is known in the art, of colors or inks which come through the printed cloth as the blanket passes over the impression cylinder of the printing machine, thus eliminating the use, and consequently the expense, of the "gray cloth" which has been heretofore used for taking up the excess color or ink passing through the printed cloth and is known to be extremely expensive.

With this and other objects in view, the invention consists in the novel construction, combination and arrangement of parts as will be hereinafter specifically described, claimed and illustrated in the accompanying drawings, in which:

Figure 1 represents a diagrammatic view in side elevation of the improved blanket washing machine, illustrating the impression cylinder of a textile printing machine, Fig. 2 represents a fragmentary longitudinal sectional view through the washing machine, and

Fig. 3 represents a fragmentary plan view of the washing machine.

Referring to the drawings in detail, wherein similar reference numerals indicate corresponding parts throughout the several views, the numerals 5 and 6 indicate the horizontal and vertical beams of the supporting frame of the machine which is arranged in proximity to the impression cylinder 7 of a textile printing machine, including the usual engraved printing roller 7^a, color furnishing roller 7^b and color pan 7^c.

The endless web or blanket 8 extends around the impression cylinder 7, between the latter and the printing roller 7^a upwardly over a guide roller 9 and the upper portion thereof is supported on a pair of rollers 10 and 11, the roller 11 being adjustable longitudinally in the frame by ad-

justing screws 12, so as to vary the tension of the blanket, as desired. From the adjustable roller 11, the blanket extends downwardly under a relatively large cylinder 13, which is supported in a liquid container 14 from which the water or other washing fluid is conducted by a drain pipe 14^a. At points on opposite sides of the adjustable roller 11, perforated sprayer pipes 15 are arranged over the blanket 8 and are designed to spray water thereon so as to soften the ink or dye prior to the entrance of the blanket into the tank or container 14.

A series of rotary brushes 16 are rotatably supported in the container 14 directly under the cylinder 13 and are arranged to operate against the portion of the blanket traveling over the cylinder 13. A plurality of sprayer pipes 16^a is arranged in the container and positioned to direct sprays of water against the blanket and brushes 16. Leaving the cylinder 13, the blanket is extended over and under guide rollers 17 and 18, respectively, and intermediate said guide rollers 17 and 18 is arranged a roller 19 which is driven at a high speed by means which will be hereinafter described, to carry off the water from the blanket 8 as the latter passes thereover. The roller 19 is engaged by a flexible blade 19^a, which is so arranged as to carry off and direct water into the container 14.

Adjacent the roller 18 are arranged pairs of vertically disposed uprights 19^b in which are supported vertical rows of drying cylinders 20, known in the art as drying cans, which are connected with each other by gear wheels 21 and intermeshing pinions 22. The blanket 8 is extended back and forth over the rows of drying cans 20 and from the uppermost drying can said blanket is extended over a series of guide rollers 23, which latter are arranged in superposed rows.

A tensioning roller 24 is supported upon the blanket 8 for tensioning the latter and is connected with weights 25. From the guide rollers 23 the blanket 8 is extended toward the impression cylinder 7 and over guide rollers 26.

An auxiliary blanket 27 is extended over the impression cylinder 7 under the main blanket and is supported upon an adjustable roller 28 mounted in the supporting frame of the washing machine.

The operating gear wheels and pinions 21 and 22, respectively, for the drying cans

are driven by a gear wheel 28 supported upon a shaft 29, which latter is driven by belts 30, and a counter shaft 31, one of the belts 30 being connected with the impression cylinder 7 of the printing machine.

A shaft 33 is supported upon the container 14 and is connected by belts or other power transmitting devices 34 with a drive shaft 32 and is connected by a belt or chain 10 with the several rotary brushes 16, which latter rotate in a direction opposite to the direction of rotation of the cylinder 13. The roller 19 is connected with a shaft 33 by a belt or other power transmitting device 15 36, and the portion thereof which engages the under side of the blanket 8 moves in a direction opposite to that in which the blanket moves.

In operation, the fabric to be printed is 20 carried over the portion of the blanket 8 disposed upon the impression cylinder 7 and is printed in the usual manner by the engraved printing roller 7^a in connection with the printing machine. From the impression cylinder the blanket travels upwardly over the several guide rollers 9, 10 and 11 and under the cylinder 13, the water or other fluid discharged from the sprayer pipes 15 serves to moisten the ink or dye 30 on the blanket. In passing through the container 14, the blanket is subjected to water discharged by the sprayer pipe 16^a and is thoroughly washed by the rotary brushes 16 and after leaving the cylinder 35 13 the excess water or fluid is taken off of the blanket by the roller 19 and blade 19^a. As the blanket passes over the several drying cylinders 20 and guide rollers 23 it is effectively dried and cooled and travels back to 40 the impression cylinder 7 in this dry condition.

What I claim is:

1. In combination with the impression cylinder and printing roller of a textile printing machine, an endless web or blanket adapted to travel upon said impression cylinder, means for applying liquid to and scrubbing said blanket, and means for moistening said blanket preliminary to its passage over said scrubbing means.
2. In combination with the impression cylinder and printing roller of a textile print-

ing machine, an endless web or blanket adapted to travel upon said impression cylinder, means for applying liquid and scrubbing said blanket, and means located at various points between the impression cylinder and the scrubbing means for moistening said blanket preliminary to its passage over said scrubbing means.

3. In combination with the impression cylinder and printing roller of a textile printing machine, an endless web or blanket adapted to travel upon said impression cylinder, means for applying liquid and scrubbing said blanket, means for moistening said blanket preliminary to its passage over said scrubbing means, and a plurality of rollers arranged between the scrubbing means and the impression rollers and said blanket being 70 extended back and forth over said rollers so as to aerate and cool the blanket.

4. In combination with the impression cylinder and printing rollers of a textile printing machine, an endless web or blanket adapted to travel upon said impression cylinder, means for applying liquid and scrubbing said blanket, means for moistening said blanket preliminary to its passage over said scrubbing means, drying means for said blanket arranged intermediate the scrubbing means of the impression cylinder, and a plurality of rows of rollers arranged between the drying means and the impression cylinder for supporting and cooling the 85 blanket prior to its return to the impression cylinder.

5. In a blanket washing machine for textile printing machines, a container, a cylinder journaled in the container, an endless 90 blanket extending over said cylinder, means for moistening said blanket, means for scrubbing said blanket during its passage over said cylinder, a high speed roller engaging said blanket for extracting liquid 95 therefrom by pressure, and a blade engaging the roller for deflecting the liquid back into the container.

In testimony whereof I affix my signature in presence of two witnesses.

EDWARD WHITE.
